ABSTRACT

An electric fuse having blind metal fusion joints, e.g. solder joints, between the two ferrules and the fusible element, or the fusible elements, thereof. One of these conductive connection joints is situated adjacent the center region of the inner end surface of one of the two ferrules. The other of these conductive connection joints is situated between one of the rims of the casing and the peripheral region of the inner end surface of the other of the two ferrules.

2 Claims, 5 Drawing Figures

PROCESS OF MANUFACTURING ELECTRIC FUSE

This is a division of application Ser. No. 673,375, now U.S. Pat. No. 4,041,525, issued 8/9/77, filed 4/5/76 for *Electric Fuse and Process of Manufacturing The Same*.

BACKGROUND OF THE INVENTION

This invention refers to electric fuses having a tubular casing of electric insulating material which is closed on the ends thereof by ferrules, or terminal caps. The ferrules, or terminal caps, are conductively interconnected by one or more fusible elements. The ends of a fusible element or of fusible elements are generally conductively connected to the ferrules either by spot welds, or by solder joints. There are a great many ways of establishing electrically conductive joints. Solder joints of the kind under consideration are classified into two classes, of which one class is referred to as blind solder joints. Blind solder joints are generally not visible. 20 Therefore fuses having blind solder joints have generally a better appearance than fuses having solder joints which are visible from the outside thereof. As a rule, fuses having blind solder joints are less reliable than fuses having visible solder joints because, generally, the 25 soldering process cannot be observed while the solder joints are made, and because a defect in a blind solder joint may not readily be discovered by quality control methods. Conventional blind solder joints have a high ratio of non-satisfactory joints to satisfactory joints. 30 This is also due to the fact that when making conventional blind solder joints the parts to be soldered together cannot be held in engagement under pressure while the joint is made.

It is, therefore, the prime object of this invention to 35 provide electric fuses including blind electrically conductive joints between the ferrules and the ends of the fusible element or elements which fuses are not subject to the above limitations. Another object of this invention is to provide fuses wherein electrically conductive 40 joints formed between the ends of the fusible element or elements and the ferrules are not visible from the outside of the fuse structure and can be made cost effectively with a high degree of reliability.

Other objects and advantages of the invention will 45 become more apparent as this specification proceeds.

SUMMARY OF THE INVENTION

Fuses according to U.S. Pat. No. 4,041,525 include a tubular casing of electric insulating material having a pair of rims at the axially outer ends thereof. There is a granular arc-quenching filler inside the casing. A pair of ferrules each having an axially inner end surface is mounted on said casing and closes the ends thereof. The casing houses fusible element means embedded in said arc-quenching filler. One end of the fusible element means is arranged adjacent the center region of said axially inner end surface of one of said pair of ferrules and conductively connected by a first metal fusion joint to said center region, and the other end of said fusible element means is angularly bent, rests on one of said pair of rims of said casing, and is conductively connected by a second metal fusion joint to the peripheral region of said axially inner end surface of the other of said pair of ferrules.

The process of manufacturing fuses according to the above description includes the steps of mounting a first ferrule having an inner end surface on a first rim of a

5 casing of electric insulating material; inserting a fusible element in the form of a ribbon into said casing in such a way that said fusible element in the form of a ribbon slants from the center region of said inner end surface of said first ferrule to a point of the second rim of said casing; establishing a solder joint between said fusible element in the form of a ribbon and said first ferrule at said center region of said inner end surface thereof; filling said casing with a granular arc-quenching filler; 10 applying solder to said fusible element in the form of a ribbon at a point thereof engaging said second rim of said casing; mounting a second ferrule having an inner end surface on said second rim of said casing; and thereafter heating said second ferrule from the outside thereof to cause fusion of said solder and formation of an internal solder joint between said second ferrule and said fusible element in the form of a ribbon.

BRIEF DESCRIPTION OF THE DRAWINGS

FIG. 1 is a longitudinal section of some parts in the process of assembly of a fuse embodying this invention;

FIG. 2 is a section along 2—2 of FIG. 1 or, in other words, a view of the structure of FIG. 1 seen from right to left of FIG. 1;

FIG. 3 is a longitudinal section of the same parts as shown in FIG. 1 in a more advanced state of assembly;

FIG. 4 is a longitudinal section of the structure of FIGS. 1 and 3 upon complete assembly thereof; and

FIG. 5 is a section along 5—5 of FIG. 4.

DESCRIPTION OF PREFERRED METHOD

In the drawings reference numeral 1 has been applied to indicate a tubular casing of electric insulating material having a pair of circular rims 1a at the axially outer ends thereof. Ferrule 2 provided with a blade contact 2a is mounted on the left end of casing 1 and closes the left end thereof. One or more fusible elements 3 are arranged inside of casing 1. As shown in FIG. 1 and FIG. 2 two ribbon fuse links 3 are arranged in V-formation inside of casing 1. The ribbon fuse links 3 are arranged in a slanting way inside of casing 1 in such a fashion that their left ends are coextensive with the center region 2b of the inner end surface of ferrule 2. A first solder joint 4 conductively connects the left ends of ribbon fuse links 3 to the center region 2b of the inner end surface of ferrule 2. The right ends 3a of ribbon fuse links 3 are angularly bent and rest on the right rim 1a of casing 1.

FIG. 3 is identical with FIG. 1, except that the former shows two layers of paste solder 5 on the ends of fusible elements 3 which rest upon the right rim 1a of casing 1. FIG. 3 further shows in the way of an exploded view a second ferrule 6 having a blade contact 6a which ferrule is intended to be mounted on the right end of casing 1. Prior to this casing 1 is filled with a granular arc-quenching filler 7, e.g. quartz sand. When ferrule 6 is mounted on the right end of casing 1, the peripherally outer portion 6b of the inner end surface of ferrule 6 engages under pressure the paste solder blobs 5 on ends 3a of fusible elements 3 and compress the same. As a result, they spread evenly over the ends 3a of the fusible elements 3 which rest upon rim 1a of casing 1. Upon heating of ferrule 6 from the outside thereof the paste solder 3 melts and establishes a conductive connection between the right ends 3a of fusible elements 3 and the peripheral region of the inner end surface of ferrule 6. This solder operation can be performed under pressure and tends to result in an effective solder joint. In similar fashion the operation establishing solder joint

4 can be effected while the left ends of fusible elements 3 engage under pressure the center region of the inner end surface of ferrule 2. Thus all solder joints 4,5 tend to be highly reliable, though they are solder joints which are not visible from the outside of the fuse structure, i.e. 5 are blind solder joints.

While the drawings show an embodiment of the invention which includes two fuse links 3 connected in parallel, the number of fuse links may be decreased, or increased, as desired, depending upon the current-carrying capacity which the particular embodiment of the invention is intended to have. 10

It will be apparent, particularly from FIG. 2, that the two ribbon type fuse links 3 are arranged at right angles to the median plane A—A of casing 1.

The bent at the right end 3a of fusible elements 3 resting upon rim 1a of casing 1 may either be pre-formed, or formed during the assembly of the fuse. The fusible elements 3 may be provided with incisions or perforations (not shown) as generally practiced in the fuse art to establish points of increased current density where fusing currents are minimized. 20

Casing 1 is provided with circular grooves 1b as shown in FIG. 1, into which the axially inner ends of the lateral surfaces of ferrules 2 and 6 may be crimped, 25 as shown in FIG. 4.

The process of assembling a fuse according to the present invention includes the following steps. First ferrule 2 is mounted on casing 1 as shown in FIG. 1. Then one or more fusible elements are inserted into 30 casing 1 as shown in FIGS. 1 and 3, i.e. so that each fusible element slants from the center region 2b of the inner end surface of ferrule 2 to a point on the right rim 1a of casing 1. The next step consists in establishing a solder joint 4 — e.g. by means of paste solder — between the fusible element, or elements 3 and the center region 2b of the inner end surface of ferrule 2. Now the inside of casing 1 is filled with the granular arc-quenching 35 filler 6, whereupon paste solder 5 is applied to the right ends 3a of fusible elements 3. It will be noted that FIG. 3 shows the presence of paste solder 5 without the filling of the casing 1 with the granular arc-quenching 40 filler 7. FIG. 3 has been drawn in this fashion to better illustrate the presence of the paste solder 5 before it has been spread out by mounting of ferrule 6 on casing 1. 45 Actually the filling of casing 1 with pulverulent arc-quenching filler 7 ought to precede the application of paste solder 5.

After filling casing 1 with granular arc-quenching 50 filler 7 and mounting ferrule 6 on casing 1, the point, or points 3a of the fusible element, or elements 3 are clamped together with the paste solder 5 between the rim 1a of casing 1 and the peripheral region 6b of the inner end surface of ferrule 6. Now the ferrule 6 is heated from the outside thereof to cause fusion of the 55 paste solder 5 and formation of internal solder joints between the ends 3a of fusible elements 3 and ferrule 6.

In the case that the fuse is provided with two fusible 60 elements 3 which are connected in parallel — as shown

in FIGS. 1-5 — the fusible elements 3 ought to be of equal length and, therefore, the solder joint 4 ought to be as close as possible to the center of the axially inner end surface of ferrule 2. The same applies in case that the fuse includes more than two, e.g. three or four fusible elements. If the fuse includes but one single fusible element 3, the solder joint 4 may be more or less off center of the axially inner end surface of ferrule 2 or, in other words, in that particular instance the solder joint 4 may be positioned at any point of the axially inner end surface of ferrule 2 as long as solder joint 4 is positioned radially inwardly from the left rim 1a of casing 1 as seen in FIGS. 1, 3 and 5.

The invention is not limited to fuses whose fusible 15 elements are conductively connected to the ferrules by means of soft solder joints, but encompasses also fuses wherein the above conductive connections are effected by means of welds, in particular spot-welds. Thus solder joint 4 may be replaced by a pair of spot-welds conductively connecting fusible elements 3 to ferrule 2. In a like fashion the diverging ends of fusible elements 3 may be welded to ferrule 6, thus replacing solder joints 5.

The term "metal fusion joint" which has been applied above as well as in the following claims is intended as a generic term encompassing soft solder joints as well as welds.

I claim as my invention:

1. A process of manufacturing electric fuses including the steps of
  - a. mounting a first ferrule having an inner end surface on a first rim of a casing of electric insulating material;
  - b. inserting a fusible element in the form of a ribbon into said casing in such a way that said fusible element in the form of a ribbon slants from the center region of said inner surface of said first ferrule to a point on the second rim of said casing;
  - c. establishing a solder joint between said fusible element in the form of a ribbon and said first ferrule at said center region of said inner end surface thereof;
  - d. filling said casing with a granular arc-quenching filler;
  - e. applying solder to said fusible element in the form of a ribbon at a point thereof engaging said second rim of said casing;
  - f. mounting a second ferrule having an inner end surface on said second rim on said casing; and thereafter
  - g. heating said second ferrule from the outside thereof to cause fusion of said solder and formation of an internal solder joint between said second ferrule and said fusible element in the form of a ribbon.

2. A process as specified in claim 1 wherein the solder applied to said fusible element in the form of a ribbon at the point thereof engaging said second rim of said casing is in the form of paste solder.
